UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS SONS & MAXIM, LIMITED, OF WESTMINSTER, ENGLAND.

SIGHTING APPARATUS FOR GUNS.

No. 918,738.

Specification of Letters Patent.

Patented April 20, 1909.

Application filed May 18, 1908. Serial No. 433,489.

To all whom it may concern:

Be it known that we, ARTHUR TREVOR DAWSON, lieutenant Royal Navy, director and superintendent of Ordnance Works, and 5 GEORGE THOMAS BUCKHAM, engineer, both subjects of the King of Great Britain, residing at 32 Victoria street, Westminster, in the county of London, England, have invented certain new and useful Improvements in or 10 Relating to Sighting Apparatus for Guns, of which the following is a specification.

This invention relates to gun sighting apparatus of the kind in which the operation of setting the sighting apparatus for range 15 and deflection can be effected automatically from a distant position or fire control station where the observations relating to the range and deflection are made.

For the purpose of our invention we provide at the fire control station electric transmitters connected electrically with appropriate receivers which are situated adjacent to the sighting apparatus of each of the guns that are controlled from the fire control station and which serve to control electric motors appropriately geared with the sighting apparatus and possessing sufficient energy derived from any suitable source of electric supply for effectually actuating the sighting apparatus and setting it to the required range and deflection.

The transmitters at the fire control station may comprise small electric motors of any appropriate kind controlled by rotary hand switches such for example as are described in my prior British specification No. 10659 of 1907 or other means for causing a step-by-step rotary motion to be imparted to the said motors and to pointers traveling around graduated dials, or to counting drums, said pointers or drums indicating the magnitude of the range or deflection transmitted to the receivers and sighting apparatus, and being situated at both the transmitting and receiving stations, or only at the transmitting station, and operated in a manner well known in connection with fire control systems. The said receivers comprise small electric motors and electric switches, the motors being similar to those situated at the fire control station and adapted to move in synchronism therewith. These small motors operate through the intervention of the electric switches to control the current supply of the 55 sight-actuating motors, so that a change in

the movement of the receiver motors will cause a corresponding movement in the sight actuating motors.

In order that the said invention may be clearly understood and readily carried into effect, we will describe the same more fully with reference to the accompanying drawings, in which:—

Figure 1 is a side elevation of the sighting apparatus embodying the features of our invention. Fig. 2 is a plan, and Fig. 3 an end elevation of the same. Fig. 4 is a sectional view of the receiver shown on an enlarged scale, and Fig. 5 is a transverse section of the same taken on the line 1—1 Fig. 4. Fig. 6 is 70 a diagrammatic view of the electrical connections of the receiver and the actuating motor of the sighting apparatus.

The sighting apparatus to which we have shown our invention applied, is of the well known cross-connected type comprising sight bars A A¹ hinged to a bracket A² and connected together by a transverse shaft A³ and a rod A⁴, the said shaft A³ serving to impart simultaneous elevation to the sight bars 80 when the elevating gear is actuated and the said rod A⁴ serving to impart simultaneous lateral movement to the sight bars when the deflection gear is actuated as is well understood.

B¹ B² are the receivers appertaining respectively to the elevating gear and the deflection gear and C¹ C² are the electric motors for actuating the said elevating gear and deflection gear, the motors being controlled by the receivers as will be hereinafter described. The elevating motor and its receiver are carried by a stationary part of the framing of the apparatus and the deflection motor and its receiver are carried by one of the hinged sight bars so as to move therewith during the change in elevation of the sights. The motor C¹ is connected by a shaft c with a worm c¹ meshing with a worm wheel c² mounted on a shaft c³. This shaft has a pinion c⁴ gearing with a toothed wheel c⁵ on the cross-connecting shaft A³ which carries the elevating pinions that gear with the elevating racks d⁶ in the usual manner. The deflection motor C² is connected by a shaft c⁶ with a worm c⁷ 105 gearing with a worm wheel c⁸ mounted on the spindle that carries the usual deflecting screw. The shaft c of the elevating motor C¹ has a bevel wheel c⁹ gearing with a bevel pinion b on the shaft b¹ forming part of the 110

receiver B¹; the shaft c⁶ of the deflection motor C³ is provided with a similar bevel wheel c⁹ gearing with a bevel pinion b¹⁰ on the shaft b¹⁰ forming part of the receiver B². The 5 gearing of the elevating motor and that of the deflection motor are each provided with a clutch C for enabling the motors to be thrown out of gear should it be necessary to actuate the sighting apparatus by the ordinary hand 10 operated gearing with which the sighting apparatus is provided.

As the elevating motor C¹ and its receiver B¹ are similar in construction and operation to the deflection motor C² and its receiver B², it will only be necessary for a clear 15 comprehension of the invention to describe one of these apparatus.

The elevating receiver B¹ comprises in the example shown a spindle b² (Figs. 4 and 5) 20 which is capable of being revolved in a step by step manner in either direction by means of electro-magnets b³ b⁴ when the latter are energized. These electro-magnets control pivoted armature levers b⁵ b⁶ which are situated at opposite sides of the spindle b². They carry at their upper or free ends hinged 25 spring controlled pawls b⁷ b⁸ one of which drives a ratchet wheel b⁹ and the other a ratchet wheel b¹⁰. These ratchet wheels are 30 attached to the spindle b² with their teeth directed in opposite directions so that when one of the armature levers is actuated it drives the spindle in one direction and when the other armature lever is actuated it drives 35 the said spindle in the opposite direction. Working in conjunction with the spindle is the electric switch through the intervention of which the current supply to the motor C¹ is controlled for changing the elevation of 40 the sighting apparatus in accordance with the movement of the electro magnets b³ b⁴. In the example shown this switch comprises a drum D, which is loosely mounted on the end of the spindle b² remote from the afore- 45 said ratchet wheels b⁹ b¹⁰. This drum is adapted to be revolved in the said spindle by means of a worm wheel d gearing with a worm b¹¹ on the shaft b¹ which, as before stated, receives motion from the elevating 50 motor C¹ through the bevel gearing c⁶ b¹. This drum carries integrally therewith three portions or rings d¹ d² d³ which are insulated from the said drum. The portions d¹ d² are electrically connected together but the portion d³ is insulated from the other two portions. The portions d² d³ are formed with 55 spiral or helical grooves on their periphery which grooves communicate by a steeper spiral groove d⁴ extending through an insulated block or piece d⁵. Mounted on the said spindle b² is a hollow insulated drum E which is adapted to revolve with said spindle and also to slide longitudinally thereon, for which purpose the shaft is made of rectangular 60 shape in cross-section at this part. The 65

said drum E carries a swiveling spring contact piece e which engages with the spiral grooves in the periphery of the drum D. Bearing on the drum E and the portions or rings d¹ d² of the drum D are brushes e⁵ d⁶ d⁷ forming part of the electric circuit of the apparatus as hereinafter described. The 70 said receiver is also provided with relays or electro-magnetic switches G H which control the direction of the current passing through the elevating motor C¹ and the direction of revolution of the latter, so that the elevation of the sighting apparatus can be increased or diminished as required.

We will now describe the working of the 80 apparatus with reference more particularly to Fig. 6:—

1, 2 are the mains leading the current to the elevating motor C¹ through the contacts g¹ g² h¹ h² controlled by the electric magnets or 85 relays G H. 3, 4 are other mains leading the current to the brushes e⁵ d⁶ d⁷ of the insulated rings d¹ d² d³ and to the windings of the said relays G H.

5, 6, are branch mains leading from the 90 mains 3, 4 to the rotary transmitting switch A¹ which operates the electro magnets b³ b⁴ of the pawl and ratchet driving gear for the shaft b² carrying the sliding drum E and its contact piece e.

95 First let it be assumed that the said contact piece e is resting upon the insulated piece d⁵ of the drum D, in which case the circuit through the receiver will be open and the elevating motor will remain at rest by 100 reason of the relays G H being both inactive and the contacts they control open. Now let it be assumed that the rotary transmitting switch A¹ at the fire control station has been set to work in the direction which 105 operates the electro magnet b⁴ of the pawl and ratchet device for driving the shaft b² of the receiver. Then, electrical impulses will be sent to the electro magnet b⁴ and a step by step rotary motion will be thereby imparted to the said shaft b² together with the 110 drum E and its contact piece e. As soon as the contact piece e leaves the insulated piece d⁵, the circuit from the mains 3, 4 will be completed through the rings d¹ d² and brush 115 d⁶ of the drum D and the relay G, whereupon the contacts g¹ g² appertaining thereto will be closed and current from the mains 1, 2, permitted to flow through the elevating motor which will then operate to cause the angle 120 of elevation of the sighting apparatus to be changed in a direction, let us say, to increase the elevation. During this operation the contact piece will travel in the spiral grooves of the ring d³ and the drum E carrying the 125 contact piece will move longitudinally along the shaft b² toward the left. At the same time the drum D will also be rotated from the elevating motor through the shaft b¹ and the worm gearing b¹¹ d, in a direction to coun- 130

teract the longitudinal movement of the drum E and its contact piece, with the result that when the step-by-step rotation of the shaft b^2 ceases, which will occur as soon as 5 the rotary transmitter switch at the fire control station is no longer actuated, the continued movement of the drum D by the elevating motor will move the drum E and its contact piece along the shaft b^2 toward the 10 right, thus returning said contact piece to its original position in which it will again bear upon the insulated piece d^5 . The circuit through the relay G will then be broken and the contacts g^1 g^2 will be opened by 15 springs or other mechanical devices, thereby breaking the circuit from the mains 1, 2 through the elevating motor which will accordingly come to rest.

Now let it be assumed that the rotary transmitting switch at the fire control station is rotated in the direction which operates the electro magnet b^3 of the pawl and ratchet device of the receiver. Then this electro-magnet b^3 will cause a step by step rotation 25 to be imparted to the shaft b^2 but in the reverse direction to that above stated. The contact piece e of the drum E will then leave the insulated piece d^5 and enter the spiral grooves of the ring d^2 thereby completing 30 the circuit from the mains 3, 4 through the ring d^2 and brush d^7 of the drum D and the relay H. The contacts h^1 h^2 appertaining to this relay will thus be closed and current from the mains 1, 2 will flow through the elevating motor field coils in the same direction but in the armature in the reverse direction to that above stated when the relay contacts g^1 g^2 were closed. The said motor will then operate to cause the angle of elevation 35 of the sighting apparatus to be changed in a direction to diminish the elevation. During this operation the contact piece will travel in the spiral grooves of the ring d^2 , and the drum E carrying the contact piece will move 40 longitudinally along the shaft b^2 toward the right. At the same time the drum D will also be rotated by the elevating motor through the said bevel gearing b^4 d , in a direction to counteract the longitudinal movement of the drum E and its contact piece, until the insulated piece d^5 and the contact piece e again coincide, whereupon the circuit through the relay H will be broken and the relay contacts h^1 h^2 opened. The flow of 45 current to the elevating motor from the mains 1, 2 will therefore cease and the motor will come to rest. It will thus be seen that the effect of rotating the drum E by the step by step rotation imparted to the shaft 50 b^2 by one or other of the electro-magnetic pawl devices, is to cause the contact piece e to move in one or other direction away from the insulated piece or neutral point d^5 on the drum D, and that the effect of rotating the 55 drum D by the elevating motor is to counter-

act this movement so that when the drum E is no longer moved by the electro-magnetic pawl devices, the contact piece e will regain its position of coincidence with the neutral point d^5 and stop the motor. The number of 70 revolutions performed by the elevating motor and the consequent extent of movement imparted thereby to the sighting apparatus thus depends upon the electrical impulses transmitted to the electro-magnetic pawl 75 devices from the fire control station, such impulses depending of course upon the amplitude and degree of change to be effected in the elevation of the sighting apparatus to accord with the variations in range. 80

The spiral grooves in the rings d^2 d^3 of the drum D are made of sufficient length on either side of the neutral point d^5 to permit the contact piece e to travel far enough in either direction to accumulate all the step by 85 step movements of the electro-magnetic pawl devices required for transmitting the maximum range, so that should the elevating motor circuit be broken, the receiver will record the amount of range that may have 90 been transmitted, and on remaking the motor circuit, the motor will run in the required direction, until the range already transmitted has been given to the sighting apparatus and the neutral point d^5 coincides 95 with the contact piece e .

Although we have described the aforesaid receivers as being provided with step by step pawl and ratchet devices for actuating the same, we do not desire to limit ourselves 100 thereto, as any other appropriate form of motors adapted to work synchronously with the motors at the fire control station may be employed for this purpose.

It will be seen that by our invention the receiver motors operate more or less like an electric relay to bring into action a sufficiently powerful force for efficiently performing the mechanical operation of actually setting the sighting apparatus for range and 105 deflection.

What we claim and desire to secure by Letters Patent of the United States is:—

1. In electrically actuated gun sighting apparatus adapted to be controlled from a 110 distance, the combination with electric transmitting apparatus situated at the control station, of electro-magnets situated in proximity to the sighting apparatus, a spindle provided with ratchet wheels having oppositely inclined teeth mounted thereon, pivoted armature levers situated at opposite sides of the spindle and spring controlled pawls arranged to engage with the ratchet 115 wheels, a switch controlled by the electro-magnets, and a sight actuating motor controlled by the switch substantially as described.

2. In electrically actuated gun sighting apparatus adapted to be controlled from a 120

distance, the combination with electric transmitting apparatus situated at the control station, of a receiver motor situated in proximity to the sighting apparatus of each of the 5 guns to be controlled, a drum rotatably mounted on the receiver motor spindle, a plurality of rings mounted on said drum and insulated therefrom, an electrical connection between two of such rings, an insulated piece 10 situated between helically grooved convolutions formed on two of such rings, a hollow insulated drum adapted to revolve with the receiver motor spindle and also to slide thereon, a swiveling spring contact piece carried

by the said drum, a sight actuating motor 15 operatively connected with the drum that is rotatably mounted on the receiver motor spindle and means connected with the said drums for controlling the current supply to the sight actuating motor substantially as 20 described.

In testimony whereof we affix our signatures in presence of two witnesses.

ARTHUR TREVOR DAWSON.
GEORGE THOMAS BUCKHAM.
